U.S. PATENT DOCUMENTS

CLAIM

The ornamental design for a printer as shown and described.

DESCRIPTION

FIG. 1 is a perspective view of a printer showing the new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines immediately adjacent to shaded areas depict bounds and features which form no part of the claimed design, while all other broken lines are directed to environmental structure. The broken lines form no part of the claimed design.

1 Claim, 8 Drawing Sheets
